CLAIM

The ornamental design for a digital audio disc player for automobile, as shown and described.

DESCRIPTION

FIG. 1 is a perspective view of an embodiment of a digital audio disc player for automobile.

FIG. 2 is a front view of the embodiment of FIG. 1.

FIG. 3 is a rear view of the embodiment of FIG. 1.

FIG. 4 is a top view of the embodiment of FIG. 1.

FIG. 5 is a bottom view of the embodiment of FIG. 1.

FIG. 6 is a right side view of the embodiment of FIG. 1; and, FIG. 7 is a left side view of the embodiment of FIG. 1.

The broken lines in the drawings are for the purpose of illustrating portions of the digital audio disc player for automobile that form no part of the claimed design.
